UNITED STATES PATENT OFFICE.

JOHN VAN BUREN, OF BROOKLYN, NEW YORK.

FEEDING MECHANISM.

Application filed September 23, 1926. Serial No. 137,190.

This invention relates to feeding mechanism.

The invention relates more particularly to step by step feeding mechanism for wrapping or packaging machines and the mechanism is used to feed the packages through the various operating devices, such as the folding and tucking devices.

This application is a continuation in part 10 of applications Serial Nos. 611,913, filed January 13, 1923 and 11,038, filed February 24, 1925. The applications just referred to disclose respectively wrapping machines adapted to wrap gum and soap. In the 15 mechanisms disclosed, the wrapper is placed around the article to be wrapped and the ends are then folded and tucked and glued in position. The step by step feeding mechanism is used to feed the packages through 20 the folding, tucking and gluing mechanisms and it is important that a package be so fed that a wrapper will not be loosened or disarranged.

This invention has for its salient object 25 to provide step by step feeding mechanism for machines of the character described so constructed and arranged that the packages will be fed through the various operating devices without loosening or disarranging 30 the wrapper.

Further objects of the invention will appear from the following specification taken in connection with the drawings, which form a part of this application, and in which

35 Fig. 1 is an elevational view broken away showing the step by step feeding mechanism of the wrapping machine disclosed in application Serial No. 11,038;

Fig. 2 is an elevational view taken at 40 right angles to the construction shown in Fig. 1;

Fig. 3 is a sectional elevation of a slightly modified form of step by step feeding mechanism, this mechanism being disclosed in 45 application Serial No. 611,913; and

Fig. 4 is an elevational view of the construction shown in Fig. 3 taken at right angles to Fig. 3.

The invention briefly described consists 50 of step by step feeding mechanism comprising a plurality of fingers movable simultaneously to feed different packages through the different operating devices of the wrapping machine. These fingers are so mounted 55 and are so guided in their movement that

they will feed the packages downwardly in a vertical direction and in leaving the packages, will move vertically to a slight extent before any lateral movement away from the package, thereby preventing the 60 wrapper from being disarranged or loosened by reason of the movement of the fingers. Further details of the invention will appear from the following description.

In illustrating the invention, the various operating devices of the wrapping machine have been omitted and the drawings show merely step by step feeding mechanism.

In the form of the invention shown in 70 Figs. 1 and 2, the feeding mechanism is used for feeding cakes of soap. These cakes are fed by a plunger 10 into oscillatory jaws 11. As the cake is fed into the jaws 11, a wrapper is also fed into the jaws, the ends 75 of the wrapper being pressed against the ends of the cake by resilient presser fingers 12.

After the cake and wrapper have been placed in the jaws 11, the jaws are os- 80 cillated 90° or to a position in which the slot in the jaws is disposed in vertical position above a vertical guideway 15. As the cakes pass through this guideway 15, the ends of the wrapper are folded and tucked 85 in a manner fully described in my co-pending application Serial No. 11,038.

The cakes are fed vertically in the guideway to the various operating devices, three 90 cakes being operated simultaneously when the machine is running.

The vertical step by step feed comprises a pair of sets of fingers 50, 51 and 52 vertically spaced from each other and connected to or formed integral with common bars 53. The bars 53 have connected to the ends thereof, a pair of bell crank levers 54 and 55 and the pivots 56 and 57 of these levers are swung on links 58 and 59 which in turn are mounted on fixed pivots 60 and 61. 100 The bars 53 are pivotally supported at 62 and 63 at the upper ends of the bell crank levers 54 and 55 and the other ends of these levers are connected by a link 64. The lever 54, or, if desired, an arm movable with this lever is extended upwardly as shown at 65, the upper end being connected at 66 to a crank 67 which is rotated about a shaft 68 by power derived from any suitable source. As the crank rotates, the bars 53 110

and fingers 50, 51 and 52 are swung inwardly, downwardly, outwardly and upwardly to feed the packages vertically in a suitable guiding frame into which they are fed from the jaws 11.

When the jaws 11 have been oscillated through 90° to a vertical position, the fingers 50 engage the package and wrapper and force the package downwardly to a position between folding devices 70. The ends of the wrapper are then folded across the end of the article or cake and the package is again fed downwardly by means of the fingers 51 to a position in which it is acted upon by mechanism for applying adhesive to the wrapper (not shown). The package is then again fed downwardly by the bottom fingers 52 and discharged from the vertical guideway 15.

24 The fingers 50, 51 and 52 are so operated that as the crank 67 rotates the bars 53 and the fingers are swung inwardly, downwardly, upwardly and outwardly in such a manner that the fingers will not tend to move across 25 the wrapper and loosen or disarrange the wrapper.

In the embodiment of the invention illustrated in Figs. 3 and 4, the step by step feeding mechanism has been shown in connection with a machine designed for wrapping packages of gum. In this machine, the gum is fed from a hopper 75 by a plunger 76 into jaws 77 and the wrapper is fed into the jaws with the article. The jaws are then 35 rotated through 90° or to a vertical position in which the opening in the jaws is disposed in alignment with a vertical guideway 78 into which the package is discharged from the jaws.

40 The mechanism illustrated is adapted to simultaneously feed three packages through the guideway and in this guideway the wrapper is folded about the ends of the package, the ends are tucked and the folded 45 and tucked ends are glued in place. The folding, tucking and gluing mechanisms are fully disclosed in my co-pending application Serial No. 11,038, but have not been illustrated in this application since they form no part of the present invention.

In order to thus operate on three packages simultaneously, I have provided a series of 55 three pairs of feeding fingers 100, 101 and 102 rigidly fixed with respect to each other and simultaneously operated. These three pairs of fingers are formed on vertically disposed bars 103 and 104 mounted at their upper ends on a shaft 105. The shaft 105 has secured thereto an arm 106 which is connected by a crank 107 to the shaft 22 and is driven thereby. There is also secured to the shaft 105 an arm 108 to which is pivoted a link 109, the opposite end of which is pivoted at 110 on the frame of the machine.

60 The link 109 is so proportioned and pivoted

as to modify the movement of the bars 103 and 104 to give the proper and desired feeding and retracting movement to the fingers 100, 101 and 102. This movement is further accomplished by a bar or arm 111 secured to 70 the shaft 105. The member 111 extends downwardly and has mounted on its lower end a roller 112 which in turn is disposed in a track 113, thus confining the movement of the lower end of the member 111 to a reciprocating path.

75 In effect, the movement of the fingers is such that during their feeding operation they move substantially vertically downwardly. At the limit of their feeding operation, however, they are raised and moved laterally away from the path of the gum packages and are raised through a curved path and return to their initial position.

80 From the above description it will be seen that simple and practical step by step feeding mechanism has been designed and that this mechanism will feed the packages through the various operative mechanisms of the wrapping machine in such a manner that the wrappers will not be disarranged or loosened from the articles.

85 Although certain specific embodiments of the invention have been particularly shown and described, it will be understood that the invention is capable of modification and that changes in the construction and in the arrangement of the various cooperating parts may be made without departing from the 90 spirit or scope of the invention, as expressed in the following claims.

95 What I claim is:

1. In a mechanical movement, a rotatable driving member, a driven member, driving connections between said members and means for guiding the driven member in a manner whereby the rotational movement of the driving member will impart to the driven member a substantially straight line movement in one direction and a backing off and curved movement in the opposite direction.

100 2. In a mechanical movement, a rotatable driving member, a driven member, driving connections between said members and means for guiding the driven member in a manner whereby the rotation movement of the driving member will impart to the driven member a substantially straight line movement in one direction and a substantially straight line backing off movement and a curved return movement in the opposite site direction.

105 3. In a mechanical movement, a rotatable driving member, a driven member, driving connections between said members and means including a lever connected at one end to the driving member, intermediate its ends to the driven member and at its opposite end to a link having a fixed pivot,

for guiding the driven member in a manner whereby the rotational movement of the driving member will impart to the driven member a substantially straight line movement in one direction and a backing off and curved movement in the opposite direction.

4. In a mechanical movement, a rotatable driving member, a driven member, a lever connected at one end to the driving member, intermediate its ends to the driven member and at its other end to a link pivoted on a fixed pivot, and means for confining the other end of the driven member to a reciprocating path.

5. In a machine of the class described, package feeding means comprising fingers engageable with the package and means for imparting to the feeding fingers a straight line vertical feeding movement and a curved return movement to the feeding position.

6. In a machine of the class described, package feeding means comprising a plurality of spaced, successively acting fingers engageable with the package and means for imparting to the feeding fingers a straight

line vertical feeding movement, and a curved return movement to feeding position.

7. In a machine of the class described, package feeding means comprising a plurality of spaced, successively acting fingers 30 engageable with the package and means for imparting to the, substantially vertical feeding fingers a straight line feeding movement, and an upward, lateral movement from the packages fed on the return movement of the 35 fingers.

8. In a mechanism of the character described, a substantially vertical guiding frame for receiving and guiding packages, successively acting feeding means for feeding the packages through said frame, and means for imparting to said feeding means a substantially vertical feeding movement and an upward and lateral movement away 40 from the packages on the return movement 45 thereof.

In witness whereof, I have hereunto set my hand this 22nd day of September, 1926.

JOHN VAN BUREN.
